UNITED STATES PATENT OFFICE.

JAMES D. CRAIG, OF PHILADELPHIA, PENNSYLVANIA, ASSIGNOR TO
THOMAS H. WILSON, OF SAME PLACE.

DESIGN FOR A SHAWL.

SPECIFICATION forming part of Design No. 12,353, dated July 12, 1881.

Application filed May 21, 1881. Term of patent 7 years.

To all whom it may concern:

Be it known that I, JAMES D. CRAIG, a subject of Great Britain, residing in the city and county of Philadelphia, State of Pennsylvania, have invented and produced a new and original Design for Shawls, of which the following is a specification, reference being had to the accompanying photographs, which illustrate opposite faces of the shawl embodying my design.

¹⁰ *a* represents the binding-edge, of plain weaving; *b*, a twilled stripe; *c*, a broken wave; *d*, a twilled stripe; *e*, a line of diamonds; *f*, a twilled stripe; *g*, a broken wave; *h*, a twilled stripe; ¹⁵ *k*, a double row of palms, which are in inverted pairs. In between the pairs are diamonds *m*.

A shawl thus woven embodies five different designs, which are produced in three weaves,

the first being the plain woven edge *a*; second, ²⁰ the twilled stripes, and the third the broken waves, diamonds, and the palms.

The design is beautiful and attractive and of the order of an India shawl.

I claim—

²⁵ 1. The design for a shawl herein shown and described, the same consisting of the edge *a*, twills *b d f h*, broken waves *c g*, diamonds *e*, and palms *k*, forming a design of several parts or figures formed in three weaves.

³⁰ 2. The design for a shawl, having double rows *k* of inverted palms, with diamonds *m* between them, as shown and described.

JAMES D. CRAIG.
